US00D950072S

(12) **United States Design Patent** (10) Patent No.: **US D950,072 S**
Li (45) Date of Patent: **** Apr. 26, 2022**

(54) **WATERPROOF ANTIBACTERIAL
PROTECTIVE COVER**

(71) Applicant: **Chao Li**, Shenzhen (CN)

(72) Inventor: **Chao Li**, Shenzhen (CN)

(**) Term: **15 Years**

(21) Appl. No.: **29/699,049**

(22) Filed: **Jul. 23, 2019**

(51) **LOC (13) Cl. 24-02**

(52) **U.S. Cl. D24/190**
USPC .....

(58) **Field of Classification Search**
USPC D24/90, 190; D2/610, 622; D29/118,
D29/120.1

See application file for complete search history.

(74) Attorney, Agent, or Firm — McClure, Qualey & Rodack, LLP

(57) **CLAIM**

The ornamental design for a waterproof antibacterial protective cover, as shown and described.

DESCRIPTION

FIG. 1 is a top plan view of a waterproof antibacterial protective cover thereof;

FIG. 2 is a rear side elevational view thereof;

FIG. 3 is a perspective view thereof;

FIG. 4 is a bottom plan view thereof;

FIG. 5 is a right side view thereof;

FIG. 6 is a front view thereof; and,

FIG. 7 is a left elevational view thereof.

Broken lines appearing in the various figures illustrate environmental or other features that form no part of the claimed design.

1 Claim, 7 Drawing Sheets
